E. E. BECK.

REVERSIBLE RATCHET STOCK FOR PIPE THREADING.

APPLICATION FILED JULY 18, 1917.

1,324,442.

Patented Dec. 9, 1919.

UNITED STATES PATENT OFFICE.

EDWARD E. BECK, OF CHICAGO, ILLINOIS, ASSIGNOR TO CROWN DIE AND TOOL COMPANY, OF CHICAGO, ILLINOIS, A CORPORATION OF ILLINOIS.

REVERSIBLE RATCHET-STOCK FOR PIPE-THREADING.

1,324,442.

Specification of Letters Patent.

Patented Dec. 9, 1919.

Application filed July 18, 1917. Serial No. 181,187.

To all whom it may concern:

Be it known that I, EDWARD E. BECK, a citizen of the United States, residing at Chicago, Cook county, State of Illinois, have invented certain new and useful Improvements in Reversible Ratchet-Stocks for Pipe-Threading, of which the following, taken in connection with the drawings, is a description.

10 My invention relates to improvements in reversible pipe threading stocks and has for its object the provision in a device of this character of means whereby the reversible mechanism of the stock can be utilized as 15 the operator desires.

A further object of the invention is to produce a stock of this class whereby the die holding member may be locked in fixed position and may be quickly and easily released, as necessary.

In the accompanying drawings I have illustrated what I now consider the preferred form of my invention, although I wish to be understood as contemplating 25 such variations thereof as come within the scope of the claims, and in these drawings,

Figure 1 is a plan view of a reversible pipe threading stock embodying my invention;

30 Fig. 2 is a longitudinal section, taken on line 2—2 of Fig. 1;

Fig. 3 is a transverse section, taken on line 3—3 of Fig. 1.

The preferred form of my construction 35 comprises an ordinary reversible pipe-threading stock, consisting of a body, 4, and a collar, 5, rotatably mounted thereon. On the body, 4, are the circumferential shoulders, 6, 7, 8, upon which are mounted 40 the collars, 5, 9. The collar, 9, is positively secured to the body, 4, by means of the set screws, 10. The collar, 9, holds the collar, 5, in fixed position.

45 Formed integrally with the body, 4, are the radially disposed teeth, 11. A pawl, 12, is disposed in operative relation to said teeth, 11, and permits rotation of the collar, 5, in one direction only. When the direction of rotation of the stock is to be reversed, the pawl, 12, is released from operative engagement with the teeth, 11, thereby permitting the body, 4, to rotate with the collar, 5.

The thread-cutting mechanism is disposed within the chamber formed within

the body of the stock, and firmly locked in position by the member, 4a.

After the desired number of threads have been cut upon the pipe, in order to remove the stock, it is necessary to reverse the pawl 60 so that the stock can be turned in the opposite direction. This is necessary to overcome the frictional engagement between the die and the pipe.

The principal object of my invention is 65 the provision of means whereby the collar 5 may be positively and releasably locked to the body of the stock while the device is in operation. This I accomplish by providing in the retaining member one or more 70 openings, 14, in each of which is slidably arranged a bolt, 15. The body, 4, is provided with a plurality of sockets, 16, so positioned that at some point during the rotation of the collar, 5, each of said openings, 14, will be in registration with a socket, 16. While the collar, 5, and retaining member, 4, are in this position, the bolts or locking members, 15, can be forced downwardly into the sockets, 16, as clearly shown in Fig. 2. 80 Each of said locking members is provided with a head, 17, which terminates the downward movement of said member by positively engaging the collar, 5, as shown. The periphery of each of said heads, 17, is 85 knurled to permit of expeditious handling by the operator.

Extending at right angles to the locking members, 15, through the wall of the collar, 5, are openings, 19, shown more clearly in 90 Fig. 3. Within each of the openings, 14, is arranged mechanism for regulating the frictional engagement of a pin impinging upon the periphery of a bolt or locking member, 15.

On the periphery of each of the locking members, 15, is a circumferential shoulder, 20, which cooperates with means contained in each of the passages, 19, to terminate the upward movement of said locking members, 100 when the locking members, 15, are in the locking position, or at the downward terminal of their movement. The pins, 21, are disposed in the openings, 19, and are held in frictional engagement with said members by 105 the compression springs, 23, which are maintained in positive engagement with said pins by the set screws 24. When it is desired to release the collar, 5, from positive engagement with the body, 4, the locking members, 110

15, are raised until further movement is precluded by positive engagement of the pins, 21, and the shoulders, 20, as shown in Fig. 3. The locking members are held in this 5 raised position by frictional engagement with the pins, 21.

I claim:

1. The combination with a reversible pipe threading stock consisting of a body having 10 exterior and interior circumferential shoulders formed thereon, a collar seating on said shoulders and radially mounted on said body, and means for positively and releasably locking said collar while the device is 15 in operation.

2. The combination with a reversible pipe threading stock having shoulders formed thereon, a revoluble collar seating on said shoulders, locking members movable in passages provided in said collar and extending into sockets in the stock registering with the aforesaid passages, means for terminating the movement of said locking members in one direction, and means for releasing said locking mechanism substantially as described.

3. In a reversible pipe threading stock, the combination of a body having radially disposed teeth formed therein, a collar movable circumferentially of said body, corresponding abutting shoulders on said body and collar, a pawl arranged in operative re-

lation with the aforesaid teeth, locking members extending through passageways in said collar and into sockets in the stock, 35 and spring controlled mechanism for releasing said locking members.

4. The combination with a reversible pipe-threading stock, a collar mounted on said stock, of a plurality of locking members 40 slidably mounted in passages in said collar, each of said locking members having a head and a circumferential shoulder on the periphery, the aforesaid collar having passages corresponding with said first mentioned passages, and means in said last mentioned passages for terminating the movement of said locking members in one direction, substantially as described.

5. The combination with a reversible 50 pipe-threading stock, a collar mounted thereon, of a plurality of locking members slidably mounted in passages in said collar, each of said locking members having a head at its upper extremity and a circumferential 55 shoulder on its periphery, pins arranged in operative relation with said locking members, springs bearing against said pins, and means for maintaining the springs in engagement with said pins, substantially as 60 described.

In testimony whereof I have signed this specification.

EDWARD E. BECK.
